AWNINGS

Filed March 15, 1927

INVENTOR.

INVENTOR
CHRISTIAN P. FOGH
BY Joseph B. Gardner
ATTORNEY.

UNITED STATES PATENT OFFICE

CHRISTIAN P. FOGH, OF OAKLAND, CALIFORNIA

AWNING

Application filed March 15, 1927. Serial No. 175,463.

My invention relates to awnings and particularly to awnings of the roll-up, or furlable, type provided with side wings.

An object of the invention is to provide 5 an awning of the class described whereby the top and side wing members thereof are integrally attached and are arranged to be furled on a common member.

Another object of the invention is to provide 10 in an awning of the class described, means whereby the side wings may be disposed in operative or inoperative position independently of each other.

A further object of the invention is to provide 15 an awning of the class described which is arranged to be manipulated from the inner side of a wall on which it is mounted.

The invention possesses other objects and features of advantage, some of which, with 20 the foregoing, will be set forth in the following description of the preferred form of the invention which is illustrated in the drawings accompanying and forming part of the specification. It is to be understood, however, 25 that variations in the showing made by the said drawings and description may be adopted within the scope of the invention as set forth in the claims.

Referring to said drawings, 30 Figure 1 is a perspective view showing the awning of my invention mounted on a wall and operatively disposed.

Figure 2 is an end view of the showing of 35 Figure 1, the wall being shown in section.

Figure 3 is a view similar to Figure 2 showing a modified form of the invention.

As herein particularly disclosed, the awning 40 of my invention is particularly arranged for mounting on the outer side of a wall 7 of a building whereby it may provide a shade for a window 8. The awning structure comprises a roller 9 suitably mounted on the wall above the window opening and arranged to have the awning roof member 45 11, here shown as a sheet of flexible material, rolled thereon when the awning is not in use. Fixed at the outer, or free, edge of the sheet 11 is a member 12, such member extending the full width of the sheet and serving 50 as a supporting and stiffening member for

the sheet edge. Means are provided for projecting the member 12 outwardly of the wall whereby the sheet 11 may be operatively disposed, and as here shown, such means comprises a pair of struts or arms 13 pivoted to the wall at one end and having their other ends fixed to the member 12. When, as is here shown, the arms 13 are pivoted to the wall below the roller 9, the appropriate outward swinging thereof will dispose the sheet 60 11 in operative position to provide the awning roof, such roof preferably sloping downwardly from the wall 7.

Means are preferably provided for fixedly holding the awning operatively disposed and at the same time maintaining the sheet 11 tightly stretched. Accordingly, the roller 9 is of the spring-roller type and at least one of the arms 13 has a bevel gear 14 mounted on an end of a pivot pin 15 fixed thereto. 70 Mounted in the wall to extend transversely therethrough is a crank shaft 16 provided with a crank 17 at the inner end thereof and a bevel gear 18 at its outer end disposed to operatively engage the gear 14. The arms are arranged to be held in set position in any suitable manner, as by the cooperating pawl 19 and ratchet 20 mounted respectively on the wall and crank shaft. In this manner, the arms 13 may be manipulated from the 75 inner side of the wall to be disposed and held in any desired angular relation to the wall, it being noted that the spring-roller 9 functions to hold the sheet 11 properly taut at all times and to completely roll it up as the arms 80 13 are swung upwardly against the wall. And it will be further noted that the provision for the manipulation of the awning from the inside of the wall thus provided is particularly valuable in connection with 85 awning installations for windows spaced from the ground, as in dwellings.

Fixed to the side edges of the sheet 11 are wing members 21, such members being here shown arranged to be disposed generally 90 vertically whereby they may cooperate with the roof portion of the awning in providing the desired shade. It will now be noted that if a wing 21 be disposed against a face of the sheet 11, it would be rendered inoperative 100

and, furthermore, may be rolled up on roller 9 with such sheet. Means are accordingly provided for disposing each of the wings flat against the sheet 11, and as here shown, such 5 means comprises a spring roller 22 mounted on the member 12 and having a cord or line 23 wound therearound and attached to a wing at a point thereof spaced from its edge of attachment to sheet 11 whereby the wing will 10 be resiliently urged to maintain a position against the under side of the sheet—in the present embodiment the wings are generally triangular and the line 23 is attached adjacent the free apex 24 of the wing.

15 Preferably, and as here shown, a roller 22 is provided for each of the wings, whereby the positioning of the wings may be independently effected. In order to properly dispose the wings against the sheet and at the 20 same time permit the rolling up of the wings therewith, the lines 23 preferably extend from the rollers 22 through a floating pulley or deadeye 26 carried at the outer end of a stirrup 27 extending from the roller 9 and arranged to be rolled therearound as the awning is furled.

It will now be clear that the present structure permits, and at the same time resiliently resists, the disposition of the wings to form 30 operative parts of the awning. As here shown, lines 29 are utilized in disposing the wings in desired position, such lines being run from the wing tips 24 to the inner side of the wall through appropriately positioned conduits 31 35 provided in the wall. In this manner the positioning of the wings may also be readily effected from the inner side of the wall, it being noted that release of the lines 29 to permit the wings to assume their normal position against the inner faces of the sheet 11 is necessary before the awning can be furled.

Since, in usual installations, the roller 9 extends outwardly of the wall surface, the wing edge 32 which is arranged to be disposed along the wall surface is preferably formed to parallel the wall and is cut away at its upper end to clear the roller 9. To insure a proper positioning of such edge along the wall when the wing is operatively disposed, a flat normally straight flexible member 33 is secured to the wing, such member extending from the upper end 34 of the edge 26 into the wing in generally parallel relation to the wing edge which engages the 55 awning roof member 11. The member 33 is formed of spring steel or whalebone, whereby it may be rolled up with the awning on roller 9.

If desired, and as particularly disclosed 60 in Figure 3, the wing positioning rollers 22 are mounted on the wall, in which case the deadeye stirrup 27 is fixed to the member 12, the arrangement being otherwise substantially the same as before.

65 While I have herein particularly disclosed

the awning structure of my invention as particularly arranged for the operative disposition of the wings in substantially vertical planes, obvious changes in the operative direction of lines 29 might, if desired, be arranged to effect a disposition of the wings to extend laterally outwardly of the top sheet 70 75 11. Thus the wings might be extended in coplanar relation from the awning top, whereby, in the case of windows at the same level and adjacent a common corner, the wings of their awnings nearest to said corner might abut or overlap, thereby providing, in effect, a continuous awning for the two windows at such corner. Furthermore, the wings and sheet are preferably attached only at spaced points 36 along their line of contact, thus providing vents between the wings and sheet to facilitate the escape of air from beneath the awning whereby the building up 80 85 of excessive wind pressures beneath the awning may be prevented.

I claim:

1. In combination with a shade awning for an opening through a wall, a wing member 90 fixed to said sheet along a side edge thereof, a spring roller, a line connecting said wing to said roller whereby said wing will be resiliently urged to maintain an inoperative position against a face of said sheet when the sheet is extended, and means at the inside of said wall operable to dispose and hold said wing in operative position when the sheet is extended.

2. In a roller awning, a swinging U-shaped frame adapted to be pivotally attached to a wall, a roller adapted for attachment to said wall, a fabric sheet secured at one end to said roller, and at its other end to said frame, a pair of angular fabric, side wings secured to said fabric sheet, a spring roller carried by and between the sides of said U-shaped frame, a stirrup secured to the fabric sheet near the inner end thereof, a cord secured to said spring roller and extended through said stirrup and then through an opening in the lower corner of one of said flaps, said cords adapted to hold said flap in either an operative or inoperative position.

3. In a roller awning, a U-shaped swinging frame, a roller, a sheet of fabric secured at one end to the roller and at its other end to said frame, a side wing secured to an edge of said fabric sheet, a stirrup secured to said sheet near the roller, a spring roller carried by said frame and a cord associated with said spring roller through said stirrup and said wing and providing for holding said flap in either an operative or inoperative position.

In testimony whereof, I have hereunto set 125 my hand at Oakland, California, this 29th day of February, 1927.

CHRISTIAN P. FOGH.
